UNITED STATES PATENT OFFICE

JOSEPH E. O'KEEFE, OF DUMONT, NEW JERSEY

HANDY CHART AND PENCIL

Application filed March 21, 1932. Serial No. 600,128.

This invention relates to a handy chart and pencil and has for an object the provision of a simple, compact, durable, efficient device whereby a mechanic, a draftsman, an engineer, architect, bricklayer, mason, or the like can have on hand a little compact device containing a chart on which are disposed figures useful to him for reference in connection with his work and preferably at the same time incorporate this handy chart device with a pen or pencil and an eraser so that the one device possesses several useful functions.

A further object is to provide a device of the character above described which is simple and economical to manufacture and easy to operate.

Further and more specific objects, features and advantages will more clearly appear from a consideration of the specification herein-after taken in connection with the accompanying drawing which forms part of the invention and which illustrates a present preferred form of the invention.

Briefly the invention comprises a tubular element having a hollow chamber within which a chart is disposed to be wound in one direction or another past a sight opening in the tube for observation of the figures on the chart. This chart is mounted on supports rotatable through the manipulation of suitable gearing by turning the end cap of the tube. This turnable end of the tube preferably supports an eraser. The other end of the tube or cap may or may not be provided with any well known pen or pencil construction. The device preferably may be made in sections so as to make it easy to put together and to take apart and to manufacture.

The preferred present form of the invention is illustrated in the drawing of which:

Fig. 1 is an elevation partly in section of the device shown in pencil form;

Fig. 2 is a similar view taken at right angles to Fig. 1 showing more of the interior of the mechanism in section;

Fig. 3 is a horizontal section taken on the line 3—3 of Fig. 1;

Fig. 4 is a horizontal cross section on the line 4—4 of Fig. 1;

Fig. 5 is a detailed section of the manner

in which the end of the roll or chart is fastened to the supporting rod.

In the preferred form of the invention the device is embodied in the form of an elongated tube 10 having a chamber 11 throughout most of its length. This tube has preferably integral caps 12 and 13 at its opposite ends. As shown in the drawing the tube may be formed in two elongated semi-cylindrical pieces such as 14 and 15 shown in Fig. 3. It may, however, be made in one piece with the caps 12 and 13 removable.

At the lower end the tube is exteriorly threaded as at 16 and a pencil portion 17 having an interiorly threaded sleeve-like end 18 is screwed onto the elongated tube and is provided with the usual tapered end 19 containing the slideable lead 20 operated in any well known manner by the manipulation of a spiral slot and pin arrangement roughly indicated by the numeral 21. This lead in the usual manner is fed forward and backward by turning the tapered end 19 in one direction or the other. At the other and upper end of the tube it is exteriorly threaded as at 22 and there is disposed thereover a cap 23 having an interiorly threaded sleeve 24 to be threadably screwed on the upper end of the tube. This cap 23 has a central bore 25 to receive a turnable stub shaft 26 loosely therein. The outer end of this shaft is fixed on a cup shaped casing 27 and carrying an embedded eraser 28 therein. This casing 27 is turnable to turn the stub shaft 26. The other end of this stub shaft is journaled in a bore indicated by the dotted lines 29 in the cap 12. The stub shaft has thereon a gear 30 meshing on opposite sides with adjacent gears 31 and 32 which are respectively disposed on sleeves 33 and 34 rotatably journaled in grooves 35 and 36 formed in the cap 12. These sleeves receive the upper ends respectively of rods 37 and 38 the other ends of which are journaled in any suitable bores, not shown, in the lower cap 13.

These rods, one of which 37, is shown in Fig. 5 in section, are adapted to receive respective ends of a roll of material such as a chart 39. The rods are fastened to the ends of this roll or sheet of material by means of

a spring or wire 40 passing through a transverse aperture 41 in the rod 37 and through holes such as 42 in the material and tied there-around as indicated in Fig. 5, thus fastening 5 the respective ends of the sheet of material to the respective rods supporting it.

It will be obvious that as the cup shaped casing 27 is turned it turns the shaft 26 which turns the gear 30. The engagement 10 of the gear 30 with gears 31 and 32 turns the sleeves 33 and 34 in opposite directions, this causes turning of the rods 37 and 38 and consequential rolling or winding of the sheet or chart 39 in one direction or the other. 15 This sheet or chart is disposed within a hollow chamber 11 beneath a longitudinal slot or sight opening 43 in the tube which opening is filled by a glass 44 preferably of the magnifying type so that indicia marked on the 20 chart as indicated at 45 may be readily observed. This chart may be arranged with tables or figures suitable for any particular type of work such as draftsmen, civil engineers, automobile mechanics, bricklayers, 25 masons, carpenters and the like so that merely by turning the eraser casing on the upper end of the device the chart or table can be turned to perceive the proper figures. This 30 operation will take place whether or not the lower end of the device is provided with a pencil. It may be provided, if desired, with a small fountain pen or other attachment.

While the invention has been described in detail and with respect to a present preferred 35 form thereof it is not to be limited to such details and forms since many changes and modifications may be made in the invention without departing from the spirit and scope of the invention in its broadest aspects. 40 Hence it is desired to cover any and all forms and modifications of the invention which may come within the language or scope of any one or more of the appended claims.

What is claimed, is:

45 1. In a combination of the class described, a tubular body portion having a chamber, a chart receiving rod rotatably disposed therein, the end of the chart wrapped around said rod, said rod having a transverse aperture 50 therein and an engaging wire or cord passing through the end of the chart and the transverse aperture in the rod to tie the chart to the rod.

55 2. In a combination of the class described, a tubular body portion having a chamber, spaced rotatable rods in said chamber, a chart connected at its ends respectively to said rotatable rods and adapted to be wound from one to the other, head portions at the ends of 60 said body portions, said heads having grooves to receive the ends of said rods as journals therefor, sleeves connected to adjacent ends of said rods and lying in said grooves, gears on said sleeves, an intermediate operating gear disposed between and

meshing with said gears, a cap detachably connected to the end of said body portion, said cap having a bore to rotatably receive an operating shaft connected to said operating gear, a cup-shaped casing on the outer end of the body portion beyond said cap and supporting an eraser, the outer end of the operating shaft being fastened to said casing whereby the turning of the casing in one direction or another will operate the shaft and the gears to turn the rods and wind the chart in one direction or another, said body portion having a sight opening through which figures on the chart may be observed. 70 75

3. In a combination of the class described, a tubular body portion having a chamber, spaced rotatable rods in said chamber, a chart connected at its ends respectively to said rotatable rods and adapted to be wound from one to the other, head portions at the ends of said body portions, said heads having grooves to receive the ends of said rods as journals therefor, sleeves connected to adjacent ends of said rods and lying in said grooves, gears on said sleeves, an intermediate operating gear disposed between and meshing with said gears, a cap detachably connected to the end of said body portion, said cap having a bore to rotatably receive an operating shaft connected to said operating gear, a cup-shaped casing on the outer end of the body portion beyond said cap and supporting an eraser, the outer end of the operating shaft being fastened to said casing whereby the turning of the casing in one direction or another will operate the shaft and the gears to turn the rods and wind the chart in one direction or another, said body portion having a sight opening through which figures on the chart may be observed. 80 85 90 95 100

4. In a combination of the class described, a tubular body portion having a chamber, spaced rotatable rods in said chamber, head portions at the ends of said body portion, said rods being journaled at their ends in said head portions, gears connected to corresponding ends of said rods, an operating gear meshing with the above mentioned gears, a cap detachably connected to the end of the body portion, said cap having a bore to rotatably receive an operating shaft connected to said operating gear and a manually operable casing on the outer end of the body portion beyond said cap, said casing being connected to the end of the operating shaft whereby the turning of the casing will operate the shaft and gears to turn the rods. 110 115 120 125

Signed at West New York in the county of Hudson and State of New Jersey this 15th day of March A. D. 1932.
